TRANSMITTER TO TRANSMIT ELECTRO-CARDIOGRAPHIC INFORMATION

Frank R. Nardi, Englewood, Colo., and Ralph E. Pasquarette, Jordan, Minn., assignors to Honeywell Inc., Minneapolis, Minn.

Filed Feb. 10, 1975, Ser. No. 548,285

Term of patent 14 years

Int. Cl. D24—02

U.S. Cl. D83—1 F

FIG. 2

FIG. 1

FIG. 1 is a front perspective view of a transmitter to transmit electrocardiographic information showing our new design; and

FIG. 2 is a top plan thereof.

The undisclosed rear portion of the transmitter is substantially plain and unornamented.

We claim:

The ornamental design for a transmitter to transmit electrocardiographic information, as shown and described.
